Primary Examiner — Susan Bennett Hattan*Assistant Examiner* — Lauren D McVey(74) *Attorney, Agent, or Firm* — Mersenne Law(57) **CLAIM**

The ornamental design for a nasal dilator, as shown and described.

DESCRIPTION

FIG. 1 is a top plan view of a first embodiment of a nasal dilator showing our new design;

FIG. 2 is a perspective view thereof, showing the dilator in an in-use state;

FIG. 3 is a three-quarter perspective view of FIG. 1;

FIG. 4 is a top plan view of a second embodiment of a nasal dilator showing our new design;

FIG. 5 is a perspective view thereof, showing the dilator in an in-use state; and,

FIG. 6 is a three-quarter perspective view of FIG. 4. The broken line showing of human facial features is directed to environment and is for illustrative purposes only; the broken lines form no part of the claimed design.
